UNITED STATES PATENT OFFICE

2,443,298

ROCKET HELICOPTER TOY

Lawrence W. Brown, Clinton, Mo.

Application February 18, 1946, Serial No. 648,235

6 Claims. (Cl. 102—37.1)

1

This invention relates to a helicopter toy and more particularly to a helicopter toy having rocket propulsion for rotating and effecting lifting of said toy into the air providing amusement with little danger of burns or fire.

The principal objects of the present invention are to provide a toy having combined rocket propulsion and helicopter action; to provide a propellant charge so arranged that the initial ignition is sufficient to lift the toy but not powerful enough to cause explosion of the device; to provide a rocket toy with a jet aperture that will retain its size throughout the burning of the propulsion charge; to provide a jet aperture in a rocket toy where the escaping burning gases will not ignite any portion of the toy; to provide a rocket toy of substantially non-inflammable material except for the charge therein; to provide a rocket helicopter toy with an explosive charge for exploding said toy at the peak of its flight; and to provide an amusing, economical and highly efficient rocket helicopter toy that is relatively safe to operate.

In accomplishing these and other objects of the present invention, I have provided improved details of structure, the preferred form of which is illustrated in the accompanying drawings wherein:

Fig. 1 is a perspective view of a rocket helicopter toy embodying the features of the present invention.

Fig. 2 is a plan view of the toy, portions being broken away to illustrate the arrangement of the fuse and jet orifice.

Fig. 3 is a vertical longitudinal sectional view through the body of the toy on the line 3—3, Fig. 2.

Fig. 4 is a transverse sectional view through the body of the toy on the line 4—4 of Fig. 2.

Fig. 5 is a perspective view of the helicopter wing.

Fig. 6 is a detail perspective view of the body of the toy, the parts thereof being shown in disassembled spaced relation.

Referring more in detail to the drawing:

I generally designate a rocket helicopter toy constructed in accordance with the preferred form of the invention. The toy preferably consists of a body 2 having a longitudinal axis arranged horizontally and including a tube 3 made substantially non-inflammable by forming same of tightly rolled paper. The rear end 4 of the tube 3 is closed by a plug 5 preferably formed of ceramic material. The plug has a tight fit into the bore 6 of the tube and if desired may be

2

cemented or otherwise secured in place with the flat rear face 7 of the plug flush with the rear end of the tube 3. The forward end of the plug 5 is provided with a conical socket 8 adapted to receive a conical projection 9 on a propulsion charge 10, said charge preferably consisting of black powder pressed into a cylindrical shape to fit into the bore 6 of the tube 3.

Approximately midway the depth of the socket 8 the plug 5 is provided with an aperture 11 preferably extending radially through the wall of the plug and downwardly at approximately a thirty degree angle to a horizontal line perpendicular to the longitudinal axis of the body 2. The aperture 11 aligns with a recess 12 in the conical projection 9 of the propulsion charge 10 and an aperture 13 in the tube 3. The apertures 11 and 13 and the recess 12 are of such size to receive a standard size fuse 14 of suitable length, the inner end of said fuse resting in the recess 12 in contact with the charge 10 so any burning of the fuse will ignite said charge. The fuse 14 is preferably held in the apertures by an adhesive tape 15 such as Cellophane tape, said tape being wrapped around the fuse adjacent the tube 3 and the ends 16 of the tape are drawn upwardly over the top of the tube where said ends are secured to the tube in lapping condition.

While I have described the fuse 14 and jet apertures as being located at an angle of approximately thirty degrees with the horizontal, it is obvious other angularities would provide the same jet propulsion with some difference in the lift provided by said jet.

In order to provide a helicopter action to the rocket toy, a horizontal wing 17 is located near the front of the body 2 and secured above the horizontal longitudinal axis thereof by suitable fastening means. The wing may be any suitable material, but preferably consists of a metal strip 18 mounted edgewise in a vertical transverse slot 19 in the tube 3, the ends of said strip extending laterally of said tube. The ends are twisted in opposite directions at a point 20 adjacent the tube to provide blades 21 and 22 having opposing edges bent upwardly at an angle or a reverse warp in said blades which will tend to lift the toy from the ground when said toy is rotated end for end. The upper edge 23 of the blade 21, located on the same side of the tube as the jet aperture, is twisted toward the rear of the device and the upper edge 24 of the opposite blade 22 is twisted toward the forward end of the tube as illustrated to obtain the lifting effect. The wing may be secured to the tube by means of an

adhesive tape which has one end 25 secured to the top of the tube at the rear of the slot 19. The other end 26 of the tape extends over the front of the tube and is turned under the tube where it is secured to said tube to securely hold the wing in place.

If desired, the toy may be provided with an explosive charge 27 at the forward end of the propulsion charge, said explosion charge being ignited when the propulsion charge has substantially completed its burning or at the peak of the flight of the toy, thereby providing a loud noise to add to the amusement provided by the device. The explosive charge may be of any suitable material such as a pellet of granulated black powder. When an explosive charge is used in the toy, the forward end of the tube is provided with a packing or wadding 23 of fiberboard which is tightly pressed to prevent igniting thereof. The packing 23 is pressed into the tube 3 into contact with the explosive charge 27 where it seals the forward end of the tube.

The operation of the rocket helicopter toy constructed as described is as follows:

The toy is placed on the ground or other suitable surface with the longitudinal axis of the body horizontal and the wing 17 on the upper side of said body. The fuse 14 is then ignited. Burning of the fuse will direct a flame into the recess 12 in the conical projection 9 of the propellant charge 10 to ignite same creating gases which will escape through the apertures 11 and 13 in the plug 5 and tube 3 respectively. The projection 9 of the charge 10 is small thereby preventing too rapid initial burning and formation of sufficient gas to explode the toy. The force of the escaping gases through the jet apertures 11 and 13 will cause the toy to rotate or spin and be lifted by the wing 17, the body turning end for end and the longitudinal axis of the body remaining substantially horizontal during the rotation and lifting action. The location of the jet aperture radially and below a horizontal line perpendicular to the longitudinal axis of the body of the toy also provides lift thereto. When the propellant charge is burned and the toy is at approximately the peak of its flight, the explosive charge is ignited from the propellant charge. The explosive charge will cause a loud noise and also the force of the explosion will blow out any flames if any portion of the toy should become ignited; however, there is substantially no danger of fire in the use of this toy as the tightly wound paper tube 3 is substantially non-inflammable and the wing is toward the front on the opposite end of the tube from the jet apertures 11 and 13.

The plug 4 being of suitable ceramic materials prevents enlargement of the aperture 11 due to burning and maintains an even propulsion of the toy throughout its flight.

It is believed to be obvious that the present invention combines rocket propulsion and helicopter action in a safe amusement toy.

What I claim and desire to secure by Letters Patent is:

1. A toy of the character described, a horizontal body member having a longitudinal bore therein, a substantially horizontal wing mounted on the top of the body member including laterally reverse warped extending blades adapted to lift the toy when said body member is rotated end for end, a non-inflammable means closing one end of the bore in the body member and having a laterally arranged jet aperture, a pro-

pulsion charge in the bore, means extending through the jet aperture and having contact with the propulsion charge for igniting the propulsion charge adjacent the bore closing means whereby gases formed by burning the charge are discharged through the jet aperture to effect end for end rotation of the body member, and an explosive charge in the bore of the body member in contact with the propulsion charge on the opposite end thereof relative to the jet aperture whereby said explosive charge is ignited at the termination of the burning of the propulsion charge.

2. A toy of the character described, a horizontal body member having a longitudinal bore therein, a substantially horizontal wing mounted on the top of the body member including laterally extending reversely warped blades adapted to lift the toy when said body member is rotated end for end, ceramic means closing one end of the bore in the body member and having a laterally arranged jet aperture, a propulsion charge in the bore having a reduced portion adjacent the bore closing means, means extending through the jet aperture and having contact with the reduced portion of the propulsion charge for igniting said reduced portion whereby gases formed by the initial burning the charge are progressively increased and discharged through the jet aperture to effect end for end rotation of the body member, and an explosive charge in the bore of the body member in contact with the propulsion charge on the opposite end thereof relative to the jet aperture whereby said explosive charge is ignited at the termination of the burning of the propulsion charge.

3. A toy of the character described, a horizontal body member having a longitudinal bore therein and a laterally and downwardly directed aperture extending through the wall of said body member adjacent one end thereof, means mounted adjacent the other end of the body member and having laterally extending reversely warped blades adapted to lift the toy when said body member is rotated end for end, a ceramic plug in the bore adjacent the aperture in the body member, said plug having a radially arranged aperture aligned with the aperture in the body member providing communication from outside the body to the bore therein, a propellant charge in the bore of the body member and having a reduced portion adjacent the plug, and a fuse extending through the aligned apertures and having contact with the propellant charge for igniting same, the burning of said propellant charge forming gases for discharge through the aligned apertures to effect rotation of the body member, the gases formed by the initial burning of the propellant charge being insufficient to explode the toy.

4. A toy of the character described, a horizontal body member having a longitudinal bore therein and a laterally and downwardly directed aperture extending through the wall of said body member adjacent one end thereof, a substantially horizontal wing mounted on top of the body member adjacent the other end thereof and having laterally extending reversely warped blades adapted to lift the toy when said body member is rotated end for end, a non-inflammable plug in the bore adjacent the aperture in the body member, said plug having a radially arranged aperture aligned with the aperture in the body member providing communication from outside the body to the bore therein, a propel-

lant charge in the bore of the body member and having a reduced portion adjacent the plug, a fuse extending through the aligned apertures and having contact with the reduced portion of the propellant charge for igniting same, the burning of said propellant charge forming gases for discharge through the aligned apertures for effecting rotation of the body member, the gases formed by the initial burning of the reduced portion of the propellant charge being insufficient to explode the toy, and an explosive charge in the bore of the body member and in contact with the opposite end of the propellant charge from the reduced portion whereby said explosive charge is ignited at the end of the burning of the propellant charge.

5. A toy of the character described, a horizontal body member having a longitudinal bore therein and a laterally directed aperture extending through the wall of said body member adjacent one end thereof, a horizontal wing mounted on top of the body member and adjacent the other end thereof and having laterally extending reversely warped blades adapted to lift the toy when said body member is rotated end for end, means for securing the wing to the body member, a ceramic plug in the bore adjacent the aperture in the body member having a recess communicating with said bore, said plug having a radially arranged aperture aligned with the aperture in the body member providing communication from outside the body to the recess in said plug, a propellant charge in the bore of the body member and having a reduced projection extending into the recess of the plug, a fuse extending through the aligned apertures and having contact with the projection of the propellant charge for igniting same, the burning of said propellant charge forming gases for discharge through the aligned apertures to effect end for end rotation of the body member, the initial burning of the reduced portion of the propellant charge being insufficient to explode the toy, means for securing the fuse to the body member, an explosive charge in the bore of the body member and in contact with the opposite end of the propellant charge from the projection whereby

said explosive charge is ignited at the end of the burning of the propellant charge, and a packing in the bore for confining said explosive charge.

- 5 6. A toy of the character described, a horizontal body member having a longitudinal bore therein and a laterally directed aperture extending through the wall of said body member adjacent one end thereof, a horizontal wing mounted on top of the body member and adjacent the other end thereof and having laterally extending reversely warped blades adapted to lift the toy when said body member is rotated end for end, means for securing the wing to the body member, a ceramic plug in the bore adjacent the aperture in the body member having a recess communicating with said bore, said plug having a radially arranged aperture aligned with the aperture in the body member providing communication from outside the body to the recess in said plug, a propellant charge in the bore of the body member and having a reduced projection extending into the recess of the plug, a fuse extending through the aligned apertures and having contact with the projection of the propellant charge for igniting same, the burning of said propellant charge forming gases for discharge through the aligned apertures to effect end for end rotation of the body member, the initial burning of the reduced portion of the propellant charge being insufficient to explode the toy.
